UNITED STATES PATENT OFFICE.

JACOB I. SCHAFFER, OF NEW YORK, N. Y., ASSIGNOR TO SLOTE & SCHAFFER, A CO-PARTNERSHIP CONSISTING OF REUBEN SLOTE, OF MOUNT VERNON, NEW YORK, AND SAID SCHAFFER.

DESIGN FOR A LADY'S BELT.

Application filed December 17, 1923. Serial No. 8,071. Term of patent 3½ years.

To all whom it may concern:

Be it known that I, JACOB I. SCHAFFER, a citizen of the United States, residing in the city, county, and State of New York, have invented a new, original, and ornamental Design for Ladies' Belts, of which the following is a specification, reference being had to the accompanying drawing, forming part thereof.

The figure is a plan view of the belt showing my new design.

I claim:

The ornamental design for a lady's belt as shown.

JACOB I. SCHAFFER.
